[57] **CLAIM**

The ornamental design for a cage for small climbing animals and reptiles, as shown and described.

DESCRIPTION

FIG. 1 is a front and top perspective view of a cage for small climbing animals showing my new design;
FIG. 2 is a front elevational view thereof;
FIG. 3 is a rear elevational view thereof;
FIG. 4 is a side elevational view thereof, the side opposite being a mirror image of the side shown in FIG. 4; and,
FIG. 5 is a top plan view thereof, the bottom view being a mirror image of the top view shown in FIG. 5.

FIG. 1.

FIG. 5.

FIG. 2.

FIG.3.

FIG.4.
